US0D1027686S

(12) **United States Design Patent** (10) Patent No.: **US D1,027,686 S**
(45) Date of Patent: ** May 21, 2024

(54) **BREATHALYZER**

(71) Applicant: **Changsha U De Toptech Electronic Technology Co., Ltd.**, Changsha (CN)

(72) Inventor: **Liang Li**, Changsha (CN)

(73) Assignee: **CHANGSHA U DE TOPTECH ELECTRONIC TECHNOLOGY CO., LTD.**, Changsha (CN)

(**) Term: **15 Years**

(21) Appl. No.: **29/843,330**

(22) Filed: **Jun. 21, 2022**

(51) LOC (14) Cl. **10-04**

(52) U.S. Cl.

USPC **D10/81**

(57) **CLAIM**

The ornamental design for a breathalyzer, as shown and described.

DESCRIPTION

FIG. 1 is a perspective view of a breathalyzer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings are for the purpose of illustrating portions of the breathalyzer that form no part of the claimed design.
